RECLAIMING APPARATUS

Theodore A. La Brecque, Elmira, N. Y., assignor
to The Hilliard Corporation, Elmira, N. Y., a
corporation of New York

Application December 6, 1944, Serial No. 566,882

3 Claims. (Cl. 196—16)

1

This invention relates to fluid-treating apparatus and in its more specific aspects aims to provide a unit in the nature of a reclainer capable of use in numerous different connections but primarily adapted to be employed in conjunction with the purification and reclaiming of oil and similar liquids.

Viewed from certain aspects, it is an object of the invention to provide an apparatus which will present certain functional and structural improvements over the apparatus disclosed in my prior Patents 2,161,964, of June 13, 1939; 2,159,994, of May 30, 1939; and 2,336,021, of December 7, 1943.

Among the advantages derived from the use of the present invention is that of elevating the liquid or oil to a point where it may readily be fed and flow through the reclaiming or similar apparatus; such elevating or lifting being achieved without the use of any auxiliary pump or similar apparatus.

An additional object is that of furnishing a structure such that air entrained in the oil column rising to the reclainer will be dissipated so that it does not have to follow the entire cycle through the reclaiming apparatus with consequent impairment to efficiency of the latter.

Still another object is that of furnishing an apparatus particularly intended for use in connection with oils and similar liquids and by means of which the reclaimed or purified fluid will emerge from the unit at a relatively low temperature. Accordingly, such fluid may be used substantially immediately after it flows from the reclainer and without the necessity of storing it in a receptacle wherein its excess heat may be dissipated.

A further object achieved by the use of the present invention is that of warming more efficiently the incoming fluid in its flow to the reclaiming apparatus proper. At the same time, it will be understood from a review of the present teachings, that this increase in efficiency of the initial heating cycle is actually achieved with reduction of use of the pre-heater which may form a part of the unit. Accordingly, the expense of operating the latter and the over-all expense of having the apparatus function will be decreased.

Among still further objects of the invention are those of achieving any or all of the foregoing results by the use of structures which will be relatively simple and include few parts. Thus, manufacturing costs will not be increased.

2

Also, maintenance costs will, if anything, be reduced.

With these and other objects in mind, reference is had to the attached sheet of drawings illustrating one practical embodiment, and in which the figure is a partly sectional side elevation of a reclaiming apparatus such as is generally disclosed in my prior patents and in which apparatus there has been embodied structures by means of which the foregoing results have been achieved.

As before brought out, the present invention has primarily to do with an apparatus for treating and reclaiming liquids such as oils. However, it will be appreciated that the present teachings might be advantageously employed in conjunction with the treatment of other liquids. Thus, except where otherwise indicated in the appended claims, the present drawings and following description are to be taken in an illustrative rather than in a limiting sense.

As shown in the present drawings, the numeral 5 indicates a supporting structure of any desired configuration which may conveniently mount 25 an electric motor 6. The latter drives a vacuum pump 7 as well as a displacement-type pump 8. At least one of the pistons of the latter is adjustably connected as at 9 to the operating mechanism serving to reciprocate the same and so that the range of the piston stroke may be varied.

Preferably adjacent its upper end the apparatus mounts a suitably enclosed filtering bed or assembly of proper type. Part of the enclosure is conveniently in the form of a removable lid or cover portion 11. Fluid escaping from this compartment passes through the space 12 into the vaporizing chamber 13. Preferably providing the base of the latter is a member 14 presenting a tortuous passage through the convolutions of which the oil flows under the influence of gravity. Such oil or other liquid discharges from this chamber through pipe 14. Vapors escaping from the chamber 13 conveniently flow through a tube or line 15 to a distillate-receiving tank 16.

This tank is connected by a line 17 with the vacuum pump 7. Accordingly, not alone is the interior of the tank 16 subjected to sub-atmospheric pressure or vacuum but a similar condition will prevail within the vaporizing chamber 13. Fluids which do not form distillates in the tank 16 but rather continue in the form of vapors flowing through line 17 are discharged through the vacuum pump 7 and a discharge line 18. As 55 illustrated, a further receiving tank 19 may be

interposed in the latter line and this tank, as well as similar portions of the apparatus, may be provided with drain-off cocks 20.

A supply line for the apparatus is furnished at 21 and conveniently connects with one cylinder of the pump 8 while a discharge line for purified oil or other liquids is provided at 22 and conveniently connects to the second cylinder of the pump 8. Consequently, assuming that the liquid within pipe 21 flows to a point adjacent this pump, it will be forced by the latter (through a path hereinafter described) to the filtering bed below the cover 11. In that portion of the apparatus solids entrained in the liquid will be removed therefrom. Within the vaporizing chamber 13 the oil or corresponding liquid will be separated from liquids which serve to contaminate it. These liquids will be recovered in the distillate tank 16, the tank 19, or else will be discharged in the form of gases through the stack 18. The tanks 16 and 19 may be periodically drained to recover the distilled liquids.

Now with a view to properly heating the liquid flowing through pipe 21, it will be observed that a pipe 23 is connected to the intake cylinder or portion of the pump 8. This pipe connects with a heat exchanger. The latter may take one of numerous different forms and has been shown in only somewhat diagrammatic manner in the present figure. Functionally, the exchanger will, however, provide two compartments 24 and 25, the outer of which is preferably coupled to the line 23. This compartment also connects with a line 26 extending to a pre-heating compartment or compartments 27 preferably formed in or disposed adjacent the face of the heater 28. A line 29 may extend from the pre-heater to the discharge orifice in the cover 11.

The line 14 connected with the chamber 13 for the discharge of oil or similar liquids therefrom is preferably connected to the compartment 25 of the exchanger. A line 31 extends from this compartment to the pump 8 and serves to receive liquids which are discharged through the line 22.

The functioning and regulation of the heater 28 may be controlled by an adjustable thermostat structure indicated at 30. This will permit the temperature of the pre-heater and vaporizing chamber as well as the oil flowing through the several parts of the apparatus to be controlled with nicety. The complete cycle through the apparatus will hereinafter be reviewed. For a more detailed disclosure of structure and cooperation of the several parts generally heretofore described, reference is had to the afore mentioned patents issued in my name.

Interposed between the entrance end of the pump 8 and the distillate tank 16 is a vacuum-lift unit. This conveniently takes the form of a tank or receptacle 32, the base and upper end of which are connected by lines 33 and 34 with line 21. Such connection should preferably be at a point immediately adjacent the pump 8. A further line or pipe 35 may extend from the receptacle 32 to the distillate tank 16 adjacent which it is connected by the line 15. Consequently, suction will be exerted through the latter line and a condition of vacuum will come into being within the receptacle 32. This suction or vacuum condition may be periodically interrupted by a float-controlled valve 36 governing the flow of fluid into line 35.

As will be understood by those conversant with the operation of an apparatus of this type, the assembly is frequently disposed adjacent a con-

suming element such as a Diesel or other type of engine or in a vacuum pump and where its operation may be observed by the person having control of the consuming unit. To supply this reclaiming apparatus, it is frequently desirable to locate a main tank in, for example, a basement or considerably lower level than that of the reclaiming apparatus. This tank may receive the liquids (oil) discharged by one or any proper number of consuming units. The pump 8 being of the positive displacement type and connected to lift liquid to the filter bed 10, it follows that the contaminated liquid supplied through line 21 should be caused to flow to a point immediately adjacent or actually into the cylinder of the pump 8.

This is achieved by the use of the present vacuum lift comprising the casing 32 and its associated parts, in that, with the motor 6 functioning, a condition of vacuum will exist within the tank 16 and be transmitted from the latter through line 35 to the casing 32. Such a vacuum condition will cause oil to be sucked up through line 21 and flow through lines 33 and even possibly through line 34 to the receptacle 32. When a sufficient body of liquid has built up within the latter, the float controlled valve 36 will be closed to disconnect the body of the receptacle from the source of suction.

Thereupon, liquid will be free to flow through line 33 to the entrance end of the pump 8. The line 34 not alone serves to exhaust air entrained within line 21 substantially directly to the vacuum pump 7 but also serves as an equalizing or balancing line. Additionally, it will be understood that this line 34 permits oil or other liquid to flow from the tank 32 in that in effect it serves to vent the same. As soon as the degree of suction created approaches the point where it may be inadequate to cause an uninterrupted flow of liquid from the line 21 to the pump 8, liquid will flow to that pump from the tank or receptacle 32. Thereupon, the float-controlled or other valve 36 will again connect the tank or receptacle with the source of vacuum. This will immediately cause the value of the suction on line 21 to be increased, again filling the receptacle 32; the entire cycle being repeated throughout the functioning of the apparatus.

Thus, it will be unnecessary to install a force-feed pump which will, for example, serve to feed liquid from a lower level up to the level of the reclaiming apparatus. Rather, it will be feasible to locate the latter at a convenient point and where an operator may be in constant attendance. At the same time, every assurance will exist that an uninterrupted flow of liquid to the reclaiming apparatus will continue so that the operating cycle of the latter will be in no wise interrupted.

Now, with liquid flowing from the pump 8 to the heat exchanger and especially compartment 24 thereof, it will be understood that, if the second compartment of this exchanger is filled with highly heated liquid, the incoming oil or its equivalent will be warmed to a considerable degree. Thus, the oil will flow with minimum sluggishness through line 26. Such further preheating of the oil as may be necessary to put it in proper condition for passage through the filtering bed and subsequent parts of the reclainer may be achieved by the use of the heater 28.

Accordingly, the oil flows through the filtering bed and vaporizing chamber as well as the line 14. By the latter, it is conducted to the second

compartment 25 of the heat exchanger. As will well be understood, this oil, in its flow through the tube 14, is usually at a very high temperature such that it should not be used directly in a consuming element such as a Diesel engine, vacuum pump, or similar piece of apparatus. As a consequence of its passage through the heat exchanger, the oil will be cooled to a condition such that it may be safely employed immediately upon its discharge from the line 22. As afore brought out, such discharge and flow to any desired spot is effected, for example, by the second cylinder of the pump 8.

Thus, it is obvious that, among others, the several objects of the invention as specifically afore noted are achieved. It will also be apparent that numerous changes in construction and rearrangements of the parts might be resorted to without departing from the spirit of the invention as defined by the claims.

I claim:

1. A unitary oil reclaiming apparatus including in combination liquid-filtering means, vaporizing means disposed below and connected to said filtering means to receive liquid therefrom, said vaporizing means having a vapor outlet, heating means acting to heat said vaporizing means and to correspondingly raise the temperature of the liquid therein, whereby vapor emanating from said liquid may pass through said outlet, a liquid-supply line extending to said filtering means, a liquid-discharge line extending from said vaporizing means, a pump to receive oil from said discharge line, a vacuum pump, a distillate-receiving tank connected thereto and to the outlet of said vaporizing means, a pressure pump interposed in said liquid-supply line, and means for intermittently connecting said vacuum pump with said supply line at a point adjacent said pressure pump whereby to elevate liquid within said supply line.

2. A unitary oil reclaiming apparatus including in combination liquid-filtering means, vaporizing means disposed below and connected to said filtering means to receive liquid therefrom, said vaporizing means having a vapor outlet, heating means acting to heat said vaporizing means and to correspondingly raise the temperature of the liquid therein, whereby vapor emanating from

said liquid may pass through said outlet, a liquid-supply line extending to said filtering means, a liquid-discharge line extending from said vaporizing means, a vacuum pump, a distillate-receiving tank connected thereto and to the outlet of said vaporizing means, a pressure pump interposed in said fluid-supply line, and means operative responsive to fluid flow through said supply line and connected to such line at a point in advance of said pressure pump for connecting said supply line with said vacuum pump whereby to elevate liquid within said supply line.

3. In a reclaiming apparatus, in combination, a liquid treating assembly, a vacuum pump connected thereto for decreasing pressure in at least a portion of said assembly, a fluid conducting line extending to said assembly, a pressure pump interposed in said line for elevating and supplying liquid to said assembly, a tank coupled to said line and said vacuum pump and a float-controlled valve governing the flow through said tank and whereby to intermittently connect said vacuum pump with said line to bring liquid up to a level in said line such that said pressure pump will operate to force the liquid to said assembly.
